UNITED STATES PATENT OFFICE.

GEORGE T. HANCHETT, OF NEW YORK, N. Y., ASSIGNOR TO S. FISCHER MILLER, OF SOUTH ORANGE, NEW JERSEY.

FLUSH-TANK.

1,134,126.

Specification of Letters Patent.

Patented Apr. 6, 1915.

Application filed May 28, 1913. Serial No. 769,430.

To all whom it may concern:

Be it known that I, GEORGE T. HANCHETT, a citizen of the United States, residing in the borough of Manhattan, city, county, and State of New York, have invented certain new and useful Improvements in Flush-Tanks, of which the following is a full and clear specification.

My invention relates to flush tanks and 10 the particular improvement which the invention provides resides in the control or operation of the discharge of liquid therefrom.

The objects of the invention are mainly to 15 provide an improved form of manually operated discharge control, wherein the necessity of valves and packings is avoided, and to provide an improved manual control of the discharge operation in flush tanks of 20 that type in which the discharge occurs automatically at regular intervals, independent of manual operation. In this connection it should be stated that my invention may, as a matter of fact, be quite independent of the automatic discharge, according 25 to the particular arrangement of the other parts of the apparatus in which my invention is embodied, and there need be no automatic discharge at all.

30 Another important object of my invention is to prevent discharge prior to the filling of the tank up to a predetermined level.

Flush tanks are already known in which the discharge occurs through a U-shaped trap, the long leg of which extends downward from a point above the bottom of the flush tank proper, and is inclosed at its upper end in a bell which extends below the inlet of the U-shaped trap with a suitable 35 water passageway between the two for the admission of water into the lower part of the bell, which gradually rises within the bell to a point where it overflows into the U-shaped trap. In the operation of this 40 type of flush tank discharge, the liquid normally stands in the short leg of the U-shaped trap, and is there sustained at a higher level than in the long leg of the trap by the trapped air, which has been compressed 45 within the bell and upper portion of the long leg of the trap by the rise of the liquid within the bell. When the liquid 50 in the flush tank has reached such a level as to force the level in the bell above the inlet to the U-shaped trap, the contents of the

flush tank siphon out and discharge to the outlet of the short leg of the trap until the level is reached in the flush tank, which breaks the continuity of the column of liquid and admits a new supply of air into 60 the bell and the long leg of the trap. My invention may be applied in a flush tank of this type in which the supply of liquid to the tank is continuous, so that the automatic filling and discharge of the tank take 65 place as usual or it may be applied in a flush tank of this general nature, in which the supply of liquid is cut off automatically by a float valve, or the like, at a predetermined level before the condition at which automatic discharge would occur is reached. In other words, it will be seen that the invention is applicable to automatic discharge 70 flush tanks and also to those in which the feature of automatic discharge is not present. 75

The principle upon which one feature of the invention is based resides in the manner in which the transmission of the back pressure of the column of liquid in the short leg 80 of the U-shaped trap, to the rising liquid within the bell, is overcome. Heretofore the back pressure which is transmitted by the compressed trapped air has been overcome by increasing the head of the liquid within 85 the flush tank. According to the embodiment of my invention herein shown the back pressure transmission is overcome, by relieving the compressed trapped air seal in the bell or long leg of the U-shaped trap, 90 as for example, by moving the bell or establishing an escape communication for the air into the liquid within the flush tank or in any other desired manner.

The embodiment of these principles of operation which I have selected for purposes of illustration herein, operate upon the principle of moving the bell, the liquid, as it discharges, drawing the bell back to its original position. 95

The feature of preventing premature discharge of the liquid from the tank, is of especial importance in connection with flush tanks of this particular kind, wherein a continuous escape of the liquid from the tank 100 might be caused by the premature discharge. The prevention of premature discharge is, however, not to be regarded as limited to any particular kind of flush tanks. Under the broad principle of this feature of my in- 105

vention I may prevent premature discharge in various ways, but that which I have herein shown for purposes of illustration comprises a connection between the bell, or 5 analogous member, and the hand engaged actuating member, which is incapable of transmitting to the bell, or the like, more than a predetermined force, which is insufficient to operate the bell, or the like, when 10 the flush tank is not filled up to a predetermined level, but which is sufficient for greater levels. In conjunction with this transmission mechanism or connection in the present instance, I cause the bell to be of a 15 certain prescribed weight, as by suitably proportioning the same, which weight when not submerged is too great to be moved by the force which the transmission connection can convey, but when submerged in the liquid 20 and thus buoyed thereby can be moved by the transmission connection.

In the accompanying drawings, Figure 1 is a vertical section of a portion of the flush tank having the weighted bell and the yielding connection between the bell operating lever and the hand engaged member for preventing premature discharge; Fig. 2 is a detail view of a bell operating lever connected with the hand engaged member by a yielding connection in the form of a leaf spring, and Fig. 3 is a similar view in which the bell operating lever is connected with the hand engaged member by a yielding connection in the form of a weighted lever, pivoted 35 to said bell operating lever.

Referring to Figs. 1, 2 and 3, the provision of a weighted bell and a yielding operating connection therefor are herein shown so that when the flush tank is not filled up 40 to a certain predetermined level, the bell can not be operated to discharge the liquid, but when filled to, or beyond this level, the bell is sufficiently buoyed by the liquid to enable its operation by the yielding operating connection. It is immaterial to the operation of 45 this feature of my invention whether the bell be in itself of such weight as to resist, when not submerged, operation by the yielding connection, or whether this weight be occasioned by the provision of special means. To clearly illustrate the invention I have 50 shown in Fig. 1 a bell 40, having secured to, or integral with, its upper surface a cup or vessel 41, which will normally remain filled 55 with the liquid supplied to the tank 10. A pull rod and link 42 and 43 guided in the

lug 44 is connected by a tension spring 45, with the bell operating lever 46, which latter is connected to the bell by the link 47. A stop disk or the like, 48 is fixed on pull 60 rod 42, upon the guide lug 44, so that the pull rod 42 can be lowered only to a predetermined point where it is arrested by the stop lug 48. This motion places the spring 65 45 under tension, which however is insufficient to actuate the bell 40 when the latter is not submerged, but is sufficient to effect its operation when the bell is submerged to that point at which its weight is sufficiently buoyed. 70

In Fig. 2, the principle of operation is substantially the same, the tension spring 45 being here substituted by a leaf spring 49, which is suitably secured to one end of a bell operating lever 50. 75

In Fig. 3, the bell operating lever 51 has pivoted thereto at 52 a weighted lever 53, which normally rests upon a lug 54, which projects from the end of bell operating lever 51. The unweighted end of lever 53 is suitably connected for manual operation with the link 55, so that upon pulling the link 55 the weighted lever 53 will be operated about its pivot 52, without moving bell operating lever 51 when the bell is not submerged, but when the bell is submerged the lever 53 will not move upon its pivot 52, thereby transmitting to bell operating lever 51 the pull exerted on the link 55. 80

It is obvious that many mechanical constructions may be employed to take advantage of the difference in the effective weight of the bell when submerged and when not submerged, but those herein shown will be sufficient for purposes of illustration. 85

I claim:

The combination with a flush tank having a discharge outlet, a trap leading therefrom, and an air trapping bell inclosing said outlet and normally submerged in the liquid 100 within the tank; manually operated means comprising a yielding transmission connection and a stop, adapted to transmit a limited force sufficient to move said bell when submerged to a predetermined level for releasing the liquid, but insufficient to move said bell when not submerged to said predetermined level. 105

GEORGE T. HANCHETT.
